UNITED STATES PATENT OFFICE

2,538,924

SHIPPING CASE

William T. Stearn, Cumberland, Md., assignor to
Celanese Corporation of America, a corporation
of Delaware

Application October 9, 1946, Serial No. 702,140

8 Claims. (Cl. 206—65)

1

This invention relates to a novel shipping case for textile products, and relates more particularly to a novel shipping case for transporting yarn packages such as cones, cheeses, and bobbins, or bolts of fabric.

An object of this invention is the provision of a novel shipping case adapted for transporting cones of yarn which is so devised that by simple adjustment it may be converted into a shipping case suitable for transporting bolts of fabric.

Other objects of this invention, together with certain details of construction and combination of parts, will appear from the following detailed description.

According to this invention, there is provided a shipping case comprising two substantially similar compartments connected by hinges and provided with means for locking them together. The interior of the compartments are provided with supports for holding cones of yarn. Such supports may be pivotally mounted so that when arranged to receive cones of yarn they are at an angle of 90° to the compartment wall and, when the cones of yarn are removed, turning the case on its opposite end causes the supports to rotate and fold flush with the wall of the compartment. Thus, there is formed a relatively smooth inner wall surface in each compartment for the reception of bolts of fabric.

In the drawings wherein the preferred embodiments of my invention are shown,

Figure 1 is an isometric view of a shipping case of my invention, showing the same in upright position and open, ready to receive cones of yarn,

Figure 2 is a front elevational view of a filled and closed shipping case ready for shipment, partially cut away to show the interior arrangement thereof,

Figure 3 is a fragmentary view, on an enlarged scale, showing a yarn package in a position on a support ready to receive a yarn package and a support rotated into position against the case wall,

Figure 4 is a view taken along line 4—4 in Figure 3,

Figure 5 is a front elevational view of a modified form of shipping case, partially filled with yarn packages, in which the supports are permanently fixed with respect to the case walls,

Figure 6 is a detail view, on an enlarged scale, showing a yarn package on a fixed support, and

Figure 7 is a detail view, on an enlarged scale, showing a yarn package on a fixed support at right angles to the support shown in Figure 6.

2

Like reference numerals indicate like parts throughout the several views of the drawings.

Referring now to the drawings for a detailed description of my invention, reference numeral 8 indicates generally the shipping case which is comprised of two compartments 9 hinged at 10. While the case may be made of any suitable material, it is preferably made of aluminum or magnesium to reduce the weight thereof without 10 any substantial sacrifice of strength. The compartments may be fabricated with a rib-like construction to strengthen the same. The interior of the compartments have a rib 11 and channel 12 construction. In Figure 1, the supports 13 for the yarn packages, comprising substantially triangular plates, are each pivotally mounted by means of a lug 14 journaled in a bracket 15. When rotated into inoperative position, as shown at the bottom of each of Figures 3 and 4, the supports 13 are substantially completely within the channel 12 thus presenting with ribs 11 a smooth inner case wall surface for receiving fabric or other textile materials. The bracket 15 is provided with integral ears 16 which act as stops to limit the movement of supports 13 to a position substantially 90° to the case wall.

In filling the case with yarn packages, the case is placed upright in the position shown in Figure 1 which will automatically cause the supports 13 to assume a position 90° to the case wall. The yarn packages, in this case cones of yarn 17, are then placed firmly on supports 13. A sheet of cardboard or other suitable material 18 is placed between the noses 19 of the yarn packages prior 35 to closing of the case to prevent damage to said noses. Upon removal of the yarn packages from the case at the destination, the case is inverted, i. e. turned on its opposite end, thus causing the supports 13 to fold into channels 12 to present a smooth inner wall for the reception of fabric and similar materials. Suitable locking means, generally indicated by reference numeral 20, are provided to maintain the case closed for shipment. Checks 21 are also provided to maintain 40 the compartments in open position for loading and unloading the yarn packages. As is well known, these checks make frictional contact with the floor or other supporting structure to prevent the compartments from closing.

In Figures 5, 6 and 7, there is shown a modified form of shipping case in which the supports 22 are also substantially triangular in form and have an integral bracket 23 which is fixed in any suitable manner to the wall of channel 12. While 55 the case of this type may also be employed for

shipping bolts of fabric by covering the supports with a suitable mat, it is primarily intended for the shipment of yarn packages.

Prior to the instant invention, the individual cones of yarn were wrapped in wax paper and packed in paper cartons for shipment. The shipping cases of my invention may be made quite airtight eliminating the necessity of wrapping the individual cones of yarn in wax paper, and also the use of paper cartons.

It is to be understood that the foregoing detailed description is given merely by way of illustration and that many variations may be made therein without departing from the spirit of my invention.

Having described my invention, what I desire to secure by Letters Patent is:

1. A shipping case comprising a compartment having an inner surface construction comprising alternate flat ribs co-planar with each other and channels, and yarn package supporting plates mounted in said channels and in operative position extending beyond the plane of said ribs.

2. A shipping case comprising a compartment having an inner surface construction comprising alternate flat ribs co-planar with each other and channels, and yarn package supporting plates pivotally mounted in said channels and in operative position extending beyond the plane of said ribs.

3. A shipping case comprising a compartment having an inner surface construction comprising alternate ribs and channels, and yarn package supporting plates pivotally mounted in said channels, the construction and arrangement being such that when the pivoted supporting plates are folded against the wall of the compartment they form with the ribs a substantially smooth surface.

4. A shipping case comprising two compartments hinged together, each compartment having an inner surface construction comprising alternate ribs and channels, and yarn package supporting plates mounted in said channels.

5. A shipping case comprising two compart-

ments hinged together, each compartment having an inner surface construction comprising alternate ribs and channels, and yarn package supporting plates pivotally mounted in said channels.

6. A shipping case comprising two compartments hinged together, each compartment having an inner surface construction comprising alternate ribs and channels, and yarn package supporting plates pivotally mounted in said channels, the construction and arrangement being such that when the pivoted supporting plates are folded against the wall of the compartment they form with the ribs a substantially smooth surface.

7. A shipping case comprising two compartments hinged together, and made from a metal selected from the group consisting of aluminum and magnesium, each compartment having an inner surface construction comprising alternate ribs and channels, and yarn package supporting plates pivotally mounted in said channels, the construction and arrangement being such that when the pivoted supporting plates are folded against the wall of the compartment they form with the ribs a substantially smooth surface.

8. A shipping case comprising a compartment having an inner surface construction comprising alternate ribs and channels, yarn package supporting plates pivotally mounted in said channels, and means for locking the compartments together to form a closed shipping case.

WILLIAM T. STEARN.
